Assistant Examiner — Jennifer B Salazar

CLAIM

The ornamental design for a hummingbird feeder, substantially as shown and described.

DESCRIPTION

FIG. 1 is a top, front and right side perspective view of a hummingbird feeder, showing my new design;

FIG. 2 is a bottom and back side perspective view thereof;

FIG. 3 is a front side elevation view thereof;

FIG. 4 is a back side elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the hummingbird feeder that form no part of the claimed design.

1 Claim, 8 Drawing Sheets
